CLAIM

The ornamental design for a mosaic solar cell, as shown and described.

DESCRIPTION

FIG. 1 is a top perspective view that illustrates the mosaic solar cell showing our new design;

FIG. 2 is a front side elevation view thereof;

FIG. 3 is a rear side elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken line portion of the figure drawings is included to show portions of the article that form no part of the claimed design.

1 Claim, 4 Drawing Sheets
